COMBINED RAIL ANCHOR AND TIE PLATE

Filed March 28, 1929

UNITED STATES PATENT OFFICE.

OSCAR J. SUPRENNANT AND HENRY B. BACHRACH, OF SCHENECTADY, NEW YORK.

COMBINED RAIL ANCHOR AND TIE PLATE.

Application filed March 28, 1929. Serial No. 350,726.

It is present practice in the most approved railroad track construction for the tie plate to be fastened to the wooden cross tie by screw spikes. The tie plate is held in place by cut 5 steel spikes driven into the tie and extending through holes punched in the tie plate. The rail is kept from running or creeping by rail anchors clamped on to the base of the rail at varying intervals so as to bear directly 10 against the side of the cross ties. These rail anchors are effective in but one direction. The cut spikes gradually work out due to the wave motion of the track under traffic, lose their holding power and from constant re- 15 driving, the wooden ties become what is known as "spike killed", that is the fibres of the tie are cut through so that eventually the tie rots and breaks at this point. Furthermore, the cut spikes do not hold the rail tight- 20 ly enough against the tie plate to prevent the tie plate from wearing rapidly.

The combined rail anchor and tie plate which forms the subject-matter of this application is designed to hold the rail firmly 25 down upon the tie plate and the tie plate firmly down upon the tie without the necessity of using cut spikes while the anchoring means, which is interlocked with the tie plate, acts to hold the rail against movement in 30 either direction, thus entirely eliminating the necessity of using cut spikes.

Our invention is illustrated in the accompanying drawings, wherein:—

Figure 1 is a top plan view of our rail 35 anchor and of the rail placed upon the tie;

Figure 2 is a top plan view of the rail supporting plate;

Figure 3 is a sectional view on the line 3—3 of Figure 1;

Figure 4 is a section on the line 4—4 of Figure 1;

Figure 5 is a fragmentary section showing a slight modification as regards the engagement of the plate with the rail.

Referring to these drawings, 10 designates the usual wooden tie and 11 the metal tie plate mounted thereon. This tie plate is formed on its middle line with a recess 12 defined by the shoulders 13, which recess has a 15 width exactly the same as that of the base of the rail 14. One of these shoulders 13 may be made so as to overhang the base of the rail, but preferably neither of the shoulders will overhang the base of the rail. The tie plate 20 55 11 at its middle extends beyond the side edges

of the tie and preferably both ends of this projecting portion of the tie plate are slotted or cut away as at 15, these slots extending inward from the side edges of the extension of the tie plate and being adapted to receive upwardly projecting portions of one or more rail anchors 16.

Each rail anchor has a portion extending transversely across and beneath the extension of the tie plate, this portion at one end being formed with the upwardly projecting lug 17 and at its opposite end the rail anchor is bent downward as at 18, then upward at 19 and transversely at 20 so that the portion 20 will bear against the upper face of the base of the rail 14. The curve given to the parts 18 and 19 causes this portion of the anchor to be somewhat resilient and to exert a downward pressure and clamping action upon the upper face of the rail. The portion 17 and portion 25 19 extend upward into the slots 15 and thus each anchor is held from longitudinal movement with relation to the tie. The tie plate is apertured at a plurality of points with holes for the reception of the screw spikes 21, but no cut spikes are used to hold the rail plates as the rail is held in place by the anchors 20 which cannot come off because they are disposed within the slots 15. It will be noted 30 from Figure 4 that the anchor at one end of the tie plate is reversed with relation to the anchor at the other end of the tie plate.

When the rail is put in place upon the tie plate, the anchors are driven on transversely of the tie plate until the lug 17 springs up into 35 the corresponding slot 15 when the portion 19 is forced into the opposite slot 15 as shown. The rail anchor holds the rail rigidly in place on the tie plate, eliminating entirely the use of cut spikes. The rail anchor is made of 40 45 50 55 60 65 70 75 80 85 90 95 100 105 110 spring steel and is readily driven into place and locked in the slots provided in the extended portion of the tie plate.

The bent end of the rail anchor is expanded in forcing it on to the rail so that it exerts great pressure on the base of the rail and the friction exerted between itself, the base of the rail and the tie plate holds the rail from running or creeping and inasmuch as the rail anchor is disposed in a slot on each side of the tie plate, the rail anchor is particularly effective in preventing the rail from creeping in either direction.

This construction which we have devised can be manufactured and installed at a rea-

sonable cost and will save spikes, cross ties and the consequent expense of maintenance. This combined rail anchor and tie plate eliminates track spikes, increases the life of the 5 wooden cross ties, decreases the wear between the rail and tie plate, prevents the rail from running or creeping in either direction, and improves the general track conditions.

We have illustrated the bottom of the recess 12 as being slightly canted or at an angle to the bottom of the tie plate, but obviously we do not wish to be limited to this.

We claim:—

1. A combined tie plate and anchor, the tie plate having shoulders upon its upper face between which the base of a rail may be disposed, the tie plate having means whereby it may be attached to a tie, the tie plate having extensions at opposite ends, the lateral margins of the said extension being slotted and a rail anchor extending beneath the extension and having at one end an upwardly extending lug engaging one of said slots and at its other end having an upwardly and inwardly extending clamping portion adapted to extend upward through the other of said slots and over the base of the rail and clampingly engaging the same, said anchor being somewhat resilient.
2. A combined tie plate and rail anchor comprising a tie plate adapted to rest upon a tie and formed with opposed shoulders between which the base of a rail may be disposed, the tie plate having openings through which screw spikes may be passed and the tie plate at one end being extended to project beyond the tie, the opposite margins of said extension being slotted, and an anchor of resilient metal, the anchor being formed 40 with a portion adapted to extend beneath the extension of the tie plate, one end of the anchor portion having an outwardly extend-

ing lug to extend in one of said slots, the other end of the anchor being downwardly, upwardly and inwardly and downwardly 45 curved to extend up through the other of said slots and resiliently bear against the upper face of the base of the rail.

3. A tie plate adapted to rest upon a tie and having the middle portion thereof extended in opposite directions to project beyond the tie, said extensions each being formed at its opposite margins with inwardly extending slots, an anchor associated with each of said extensions, each anchor having 55 a portion adapted to extend beneath the tie plate and at one end being formed with an upwardly extending lug to interlock in one of said slots and at the other end being downwardly, upwardly and inwardly curved 60 to extend upward into the other of said slots, and resiliently bear against the upper face of a rail disposed on said tie plate.

4. A tie plate having opposed shoulders between which a rail may be disposed and having means whereby the tie plate may be held to the tie, the tie plate having a slot extending inward from one side edge of the plate, the opposite side margin of the plate having an upwardly extending recess, and a 70 rail anchor having a portion adapted to extend beneath the tie plate and at its end being formed with an upwardly extending lug to interlock with and snap into said recess when the anchor is applied, the other end 75 of the anchor being curved to extend upwardly through said slot and then upward and inward whereby to have a resilient wedging engagement against the upper face of a rail disposed upon the tie plate.

In testimony whereof we hereunto affix our signatures.

OSCAR J. SURPRENANT.
HENRY B. BACHRACH.
